CLAIM

The ornamental design for a combined ceiling fan and decorative decal for attachment to a ceiling, as shown and described.

DESCRIPTION

FIG. 1 is a bottom plan view of a combined ceiling fan and decorative decal for attachment to a ceiling, showing my new design;

FIG. 2 is a bottom plan view of a combined ceiling fan and decorative decal for attachment to a ceiling showing a second embodiment of my new design;

FIG. 3 is a bottom plan view of FIG. 2 on a reduced scale, with the decorative decal omitted for ease of illustration; and,

FIG. 4 is a side elevational view of FIG. 3, the other three sides being identical to that shown.

The sole difference between the first and second embodiments resides in the appearance of the number of blades.
